UNITED STATES PATENT OFFICE.

JOHN BOYCE MARLING, OF HATTON, ARKANSAS.

ROTARY-BOTTOM BOAT.

1,258,428.

Specification of Letters Patent.

Patented Mar. 5, 1918.

Application filed October 6, 1917. Serial No. 195,065.

To all whom it may concern:

Be it known that I, JOHN B. MARLING, a citizen of the United States, residing at Hatton, in the county of Polk and State of Arkansas, have invented certain new and useful Improvements in Rotary-Bottom Boats, of which the following is a specification.

This invention relates to boats, and has for its object, to provide a boat so constructed that the resistance of the water will be reduced to a minimum, so that with a given amount of power a much greater speed can be obtained than has heretofore been possible with the type of boats commonly employed.

A further object of the invention is to provide a boat which will be practically unsinkable.

Further objects and advantages of the invention will be set forth more fully in the detailed description which now follows.

In the accompanying drawing:

Figure 1 is a side elevation of a boat constructed in accordance with the invention with a part thereof broken away.

Fig. 2 is an underside plan view of the boat.

Fig. 3 is a transverse, vertical section through the boat.

Fig. 4 is a transverse vertical section illustrating a slightly modified form of boat and

Fig. 5 is a detail sectional view of one of the buoyant receptacles employed in conjunction with the boat.

Like numerals designate corresponding parts in all of the figures of the drawing.

Referring to the drawing the numeral 5 designates the body of the boat, and 6 the bottom thereof. It is to be understood that this body may be of any depth, size, or shape, because the invention resides more particularly in the buoyant means by which the body is supported than in the particular form of body.

Longitudinally extending members 7, 8 and 9 carry two part bearings 10, 11 and 12, in which spindles 13 of barrel like receptacles 14, are mounted to rotate. These receptacles are water tight and consequently highly buoyant, and they serve as the supporting means for the body. A propeller 15 or other suitable driving medium is employed for furnishing motive power to the boat.

It is to be noted that in the form of the invention illustrated in Figs. 1, and 2, two rows of buoyant receptacles are employed throughout the major portion of the length 60 of the boat and that adjacent the bow of the boat, a single wider receptacle 16, is mounted in bearings 17, and that at the extreme forward portion of the boat, or at that part constituting the bow, a narrower 65 and deeper receptacle 19 is provided, the spindle 20 of which is journaled in bearings 21. All of the receptacles are preferably made of barrel shape, that is they taper in opposite directions from the center line 70 thereof. This does not in any way interfere with the function to be performed by the said receptacles as rolling supports for the boat while at the same time it adds stability to the boat and prevents the boat from 75 making excessive leeway when the wind is blowing.

One of the receptacles is shown in section in Fig. 4. I preferably provide in one of each of the receptacles a plug 22, which 80 constitutes a removable closure so that if any of the receptacles should leak and become filled or partly filled with water, it would be possible by removing the plug 22 to pump the water out of said receptacle 85 and by then turning the punctured part of said receptacle to the top and tightening down on the bearing of that particular receptacle so that it could not rotate in its bearing, such a receptacle would still serve 90 as a buoying medium for the boat, and maintain the proper trim thereof, though of course, until the leak was repaired such receptacles would not be capable of rotation.

In Fig. 3 I have illustrated a slightly modified form of the invention adapted for use on larger boats and in rougher water than the form shown in Figs. 1, 2 and 3. In this case I preferably employ three rows 100 of receptacles 14^a, 14^b, 14^c, and I make the central row larger in diameter to give the boat greater draft at the center line thereof. This increases its stability because the center line of receptacles has the effect of a 105 keel. The purpose of making the foremost receptacle 19 larger in diameter than the remaining receptacles in Figs. 1 and 2, is to cause it to set deeper in the water, and cause this receptacle to act as a prow or 110 pilot and to decrease the power of the waves against the bow of the boat.

It is to be understood that this invention is not limited to the precise construction set forth, but that it contemplates the making of receptacles of any suitable size, or proportion, or shape. It is apparent that within certain limits the larger the receptacle the better, and it is to be understood that the invention includes within its purview whatever changes fairly come within the spirit 10 of the appended claims.

Having described my invention what I claim is:

- 15 1. A boat construction comprising a body portion and a plurality of barrel shaped, rolling, buoyant receptacles which complementally are of such cubic capacity as to support said body portion by their buoyancy and provide a rolling mounting for said body portion.
- 20 2. A boat comprising a body portion, a plurality of hollow buoyant rotative recep-

tacles upon which the body is supported, each of said receptacles being of barrel shape, and an independent propelling means for the boat.

25

3. A boat comprising a body portion, a plurality of rotative buoyant receptacles for supporting the same, said receptacles being disposed in a plurality of rows throughout the major portion of the length 30 of the boat and there being one of said receptacles disposed at the bow of the boat and at the longitudinal center line of the boat, said last named receptacle being larger in diameter than the others of said recep- 35 tacles.

In testimony whereof I affix my signature in the presence of two witnesses.

JOHN BOYCE MARLING.
